UNITED STATES PATENT OFFICE.

PAUL PASQUALE PUPILLA, OF NEW YORK, N. Y.

SHAVING-BRUSH.

1,388,001

Specification of Letters Patent. Patented Aug. 16, 1921.

Application filed March 27, 1920, Serial No. 369,236. Renewed February 12, 1921. Serial No. 444,537.

To all whom it may concern:

Be it known that I, PAUL P. PUPILLA, a citizen of the United States, and a resident of the city of New York, borough of Manhattan, in the county and State of New York, have invented a new and Improved Shaving-Brush, of which the following is a full, clear, and exact description.

It is well appreciated that shaving brushes have left much to be desired in that although a brush is placed in a sterilizer, the lather is mixed in a mug containing soap and water.

This practically renders the sterilization of the brush useless, in view of the fact that the mug is repeatedly used, and consequently, the brush after passing over the face of one person is dipped into the mug again for a second application of lather and the lather remaining in the mug is contaminated so that no amount of sterilizing of any brush used during subsequent operations will serve to eliminate danger of infection.

With this in view it will be appreciated that the most ideal arrangement would be one in which the brush might be sterilized and the soap applied either directly to the face of the person to be shaven or to the brush, the lather being mixed upon the face or other portion of the body.

This has heretofore been impossible in view of the fact that it would be necessary to shave a person near a faucet, as it is necessary to moisten a brush more than once to obtain a suitable lather.

Having this in view I have now constructed a brush particularly applicable for use in connection with a sterilizer, and by means of which it will be possible to either apply soap to the bristles of the brush, or to that portion to be shaved, and to mix a separate and independent lather for each person being shaved.

A further object of my invention is the provision of a brush of this type which will provide adequate amount of water instantly available for use in forming the lather.

A still further object of this invention is the construction of a brush which will permit of a sufficient amount of water being provided to insure the production of a lather of proper consistency.

Reference is had to the attached sheet of drawings which illustrates one practical

embodiment of my invention, and in which—

Figure 1 is a sectional side view taken through a brush handle constructed in accordance with my invention, and showing the same in its normal position.

Fig. 2 is a sectional view, but showing the parts in the position which they assume while ejecting the fluid, and

Fig. 3 is a sectional view taken along the lines 3—3 of Fig. 1 in the direction of the arrow.

In all of these views like reference numerals designate similar parts, and the reference numerals 5 indicates the conventional bristles of a brush which may be set in rubber or any suitable anchoring medium such as 6, formed with a centrally disposed opening 7.

A collar such as 8 embraces the base portion of the bristles 5, and connects the brush portion to the handle, which latter includes a handle reservoir 9 having one of its ends embraced by the collar 8, its opposite end affording a slidable mounting for the cap 10.

Now referring more particularly to the sectional views it will be seen that the reservoir 9 has positioned within it a hemispherical bulb 11 secured to the base 6 which bulb is preferably formed of rubber, and is provided with a central opening 12 conveniently in alignment with the opening 7 of the anchoring medium 6. Projecting within the reservoir 9 is a tube such as 13, which tube is formed with a thickened reduced inner end portion 14, and slidably mounted within said tube and extending beyond the ends of the same is a rod 15 having one of its ends secured to the inner face of the cap 10, the opposite end mounting as at 16, a plunger 17 in alignment with the opening 12 of the bulb 11.

In operation it will be appreciated that the collar 8 may be removed from the reservoir 9, and the latter filled with pure water, subsequent or prior to which the brush may have been placed in a sterilizer of any desired type. The collar 8 is slipped over the upper end of the reservoir 9 and the brush is now ready for shaving. Upon the lather being placed upon the surface to be shaved or upon the bristles of the brush and the cap portion telescoped with respect to the reservoir 9 as has been indicated in Fig. 2, that fluid trapped within the bulb 11 will

be ejected through the opening 7 and into the bristles, thus permitting a desirable amount of lather to be made upon the surface to be shaved. In this connection it is to be noted that the water within the bulb 11 will not escape through the opening 7 during normal operation, but upon the cap 10 being moved inwardly against the action of the spring 18 interposed between the thickened inner end portion 14 of the tube 13 and inner face of the cap 10 the rod 15 and plunger 17 will be projected inwardly in the manner indicated in Fig. 2. The plunger 17 acts as a valve, by virtue of its co-operation with the opening 12 of the bulb 11 so that no fluid may escape through this opening upon the bulb being constricted, but that fluid which is entrapped within the bulb will be forced as aforesaid into the opening 7 of the bristles 5.

It is to be appreciated that that degree of adjustment most desired may be secured by virtue of the connection existing between the plunger 17 and rod 16 in that a movement on the part of the plunger 17 with respect to the rod 15 will permit a greater or less movement of the cap 10 of the reservoir 9 and consequently a regulating of the working stroke of the plunger 17 against the bulb 11.

Further it will be appreciated that this brush will render itself readily to practical use in that the same may be operated by engaging the collar 8 with two of the fingers 35 and permitting the palm to bear against the cap 10 so that its cap will be moved with respect to the reservoir 9 and result in operation of the parts as has been described.

Obviously numerous modifications of structure might be resorted to without in the least departing from the scope of my claims, which read,

What I claim as new and desire to secure by Letters Patent is as follows:

- 45 1. A brush, including bristles, a base for such bristles, said base being formed with an opening, a bulb positioned to the rear of and in communication with said opening, a handle forming a reservoir, said bulb being formed with an opening permitting of communication between the same and the reservoir forming handle, and means for actuating said bulb to expel fluid within the same through the base opening.
- 55 2. A brush, including bristles, a base for such bristles, said base being formed with

an opening, a bulb positioned to the rear of and in communication with said opening, a handle forming a reservoir, said bulb being formed with an opening permitting of communication between the same and the reservoir forming handle, and means movable with respect to said handle adapted to act upon said bulb to expel fluid therefrom through the base opening.

60 3. A brush, including bristles, a base for such bristles, such base being formed with an opening, a reservoir adapted to be secured to said base, a bulb within said reservoir, and to the rear of said base, means for constricting said bulb, said bulb having means for permitting a fluid within the reservoir to pass into said bulb.

70 4. A shaving brush, including bristles, a base for such bristles, such base being formed with an opening, a handle to the rear of said base, said handle including a reservoir, a bulb within said reservoir and secured to the rear of said base, said base being formed with an opening, a cap slidably mounted upon such reservoir, and means extending from such cap into said reservoir in line with the bulb opening, said means being adapted to be moved to bear against said bulb opening and to constrict the bulb.

80 5. A shaving brush, including bristles, a base for such bristles, such base being formed with an opening, a handle to the rear of said base, said handle including a reservoir, a bulb within said reservoir and to the rear of said base, a cap slidably mounted upon such reservoir, and a slideable rod extending from said cap into said reservoir, a plunger secured to the inner end of said rod, said plunger being in line with an opening in said bulb, and being adapted upon inward movement to close the opening and to constrict the bulb.

90 6. A shaving brush, including bristles, a base for such bristles, such base being formed with an opening, a handle to the rear of said base, said handle including a reservoir, a bulb within said reservoir and to the rear of said base, a cap slidably mounted upon such reservoir, and a slideable rod extending from said cap into said reservoir, a plunger adjustably mounted upon the end of the rod, said plunger being in line with an opening in said bulb, and being adapted upon inward movement to close the opening and to constrict the bulb.

100 PAUL PASQUALE PUPILLA.
